J. J. STEPHENS AND C. B. HARRIS.

STILT.

APPLICATION FILED APR 25, 1921.

1,427,030.

Patented Aug. 22, 1922.

UNITED STATES PATENT OFFICE.

JOSEPH J. STEPHENS, OF RICHMOND, MISSOURI, AND CLINTON B. HARRIS, OF DALLAS, TEXAS.

STILT.

1,427,030.

Specification of Letters Patent. Patented Aug. 22, 1922.

Application filed April 25, 1921. Serial No. 464,378.

To all whom it may concern:

Be it known that JOSEPH J. STEPHENS and CLINTON B. HARRIS, citizens of the United States, residing at Richmond and Dallas, 5 respectively, in the counties of Ray and Dallas, respectively, and States of Missouri and Texas, respectively, have invented certain new and useful Improvements in Stilts, of which the following is a specification.

10 The present invention relates to improvements in stilts.

An important object of the invention is to provide means whereby the foot rest may be vertically adjusted upon the bar of the stilt, 15 enabling the user to learn to walk upon the stilts, with the foot rest at low adjustment, and to elevate the foot rest, when becoming skillful in the use of the stilts.

20 A further object of the invention is to provide a foot rest which is extremely simple in construction, strong and durable.

A further object of the invention is to provide means to prevent the stilt from slipping upon the ground or the like.

25 Further object of the invention is to provide a boot which may be detachably secured to the lower end of the bar, and will aid in walking upon soft ground.

Other objects and advantages of the 30 invention will be apparent during the course of the foregoing description.

In the accompanying drawings forming a part of this specification, and in which like numerals are employed to designate like parts 35 throughout the same,

Fig. 1 is a perspective view of a stilt embodying our invention,

Fig. 2 is an enlarged section taken on line 2—2 of Figure 1, parts in elevation,

40 Fig. 3 is a detail section taken on line 3—3 of Figure 1, and

Fig. 4 is a perspective view of the boot.

In the drawings, wherein for the purpose of illustration is shown a preferred embodiment of our invention, the numeral 5 designates the bar or body portion of the stilt, which is provided with transverse openings 6, in its lower portion. These openings are preferably equidistantly spaced, as shown.

50 The numeral 7 designates a foot rest, as a whole, which is preferably formed of a strip of suitably stiff metal, bent to provide an upper U-shaped portion 8, including an inner upstanding ear or side 9, and an outer side 10. The strip is bent downwardly upon

and about the side 10, at 11, and continued in the form of a diagonal brace 12, depending therefrom, and having a depending ear 13. The ears 9 and 13 are apertured for receiving bolts 14, which are removably mounted within selected openings 6, and carrying nuts 15 and washers 16, as shown.

At the lower end of the bar 5 there is provided a U-shaped guard 17, preferably formed or bent from strap iron. The lower 65 end of the bar 5 contacts with the bottom of the bar 17, and the upper ends of the guard have openings 18, receiving a bolt 19, passing through a transverse opening 20 in the bar 5. At its bottom, the U-shaped guard 17 70 has a transverse opening 21, through which passes a pointed element or prong 22, provided at its top with a relatively large head 23. This head rests upon the top of the bottom of the U-shaped guard, and is within a 75 slight recess 24 provided in the lower end of the bar 5. It is obvious that by disconnecting the guard 17 from the bar 5, that the prong 22 may be readily removed, to be sharpened, or to permit of the insertion of a 80 new prong, should the first prong become injured.

The numeral 25 designates a boot as a whole, preferably formed of section or strap iron, bent into the desired shape. This boot 85 embodies a horizontal base 26, extending beyond the guard 17, for a substantial distance, upon opposite sides thereof. From the ends of the horizontal base 26, upwardly converging sides 27 extend, terminating in 90 parallel portions 28, as shown. The horizontal portion 26 is apertured at 29, to receive the prong 22, projecting downwardly from below. The boot therefore does not interfere with the operation of the prong, and 95 the prong serves in addition to connect the base 26 with the lower end of the bar. The parallel portions 28 are apertured for receiving bolts 30, passing through openings 31 in the bar 5. These bolts carry nuts 32. 100 It is obvious that by removing the nuts 32 that the boot may be quickly removed from the lower end of the bar.

In use, two of the stilts shown in the application, are employed. The foot rest 7 105 may be secured to each bar 5 at a lower position, and when the user becomes more skillful, the foot rest may be raised, and clamped to the bar, as is obvious. The prong 22 will tend to prevent the slipping of the stilt upon 110

the ground or the like. When the stilt is used to walk upon damp ground, grass or the like, it is preferred to employ the boot 25, which by virtue of the large contact area 5 of the base 26, will not sink into the ground or grass. The prong 22 will function to prevent slipping, when the boot is employed.

It is to be understood that the form of our invention is to be taken as a preferred example of the same, and various changes in the shape, size and arrangement of parts may be resorted to without departing from the spirit of our invention or the scope of the subjoined claims.

Having thus described our invention, we claim:

1. A stilt comprising, a bar, an approximately U-shaped guard receiving the lower end of the bar and secured thereto, the bottom of the guard having an opening, a headed prong arranged within the opening with its head between said bottom and the lower end of the bar, a boot disposed exteriorly of the guard, said boot having a

base extending laterally beyond the guard 25 and upstanding arms for connection with said bar, said base having an opening to receive the prong which extends downwardly below the base, and a foot rest carried by said bar.

2. A stilt comprising, a bar, a foot rest carried thereby, an approximately U-shaped guard secured to the lower end of the bar and having an opening in its bottom, a prong arranged within the opening and projecting outwardly beyond said bottom, and a boot disposed exteriorly of the guard and projecting laterally beyond the same and including a base and upwardly converging sides, said base having an opening to receive 40 the prong which projects outwardly beyond the same, and means for securing the upper ends of said sides to said bar.

In testimony whereof we affix our signatures.

JOSEPH J. STEPHENS.
CLINTON B. HARRIS.
